UNITED STATES PATENT OFFICE.

GEORGE F. TURNER, OF MAHONINGTOWN, PENNSYLVANIA.

AIR-COMPRESSION-CYLINDER LUBRICATOR.

Application filed June 27, 1927. Serial No. 201,771.

The present invention relates to an air compression cylinder lubricator to automatically lubricate the air compression cylinder of an air compressor machine, and primarily 5 designed for use on railway locomotives.

The device consists of a lubricator for oil reservoirs with a regulating adjustment and sight feed attached, placed in a suitable position higher or above the air compression cylinder and having a feed pipe attached, and connecting with the air compression cylinder; also consisting of an air inlet valve arrangement so designed and constructed that the air entering the air compression cylinder will create a vacuum in the oil feed line from the lubricator; this oil feed line also having a valve arranged to hold the vacuum thus created, which will cause the oil to pass from the reservoir into the feed 20 line and into the air compression cylinder in the desired quantity.

The air compression cylinder has an air inlet valve so arranged that the air inlet valve requires more pressure to open it than 25 is required by the vacuum valve in the oil feed line so that the oil feed line will thus operate to secure the desired vacuum required to cause the oil to flow from the oil reservoir to the air compression cylinder.

30 In the drawing:

Figure 1 is an elevation of the combination of parts forming the subject matter of this invention,

Figure 2 is a sectional view of a valve arrangement,

Figure 3 is an enlarged detail section taken substantially on the line 3—3 of Figure 1.

Referring to the drawings in detail it will 40 be seen that the numeral 5 denotes an oil reservoir in which extends a tube 6 to the bottom thereof and through the top thereof being connected with a regulator valve 7 and a sight feed 8. The numeral 9 denotes 45 the filler plug and the numeral 10 the air vent. The oil feed pipe 11 extends downwardly from the sight feed 8. The numeral 12 denotes the steam cylinder and the numeral 13 the air cylinder. An air valve A is 50 plugged or tapped into the air cylinder while a vacuum holding valve B is tapped into the casing of the air inlet valve.

The air inlet valve comprises a casing 14 with a valve seat opening 15 therein against 55 which is normally closed a valve 16 on a stem 17 slidable through a spider guide

structure 18 and held closed by a spring 19. The valve B consists of casing sections 20 and 21 threaded together. A perforated guide 22 is disposed in the casing through which is slidable a valve stem 23 about which is disposed a spring 24 for holding a valve 25 on the stem closed against the opening 26. The pipe 11 is connected to the upper end of the casing 20 by means of suitable coupling 27 or in any other desired manner. The two valves 16 and 25 are held in place by their respective coil springs as explained. The feed line valve connections and oil reservoir must have air-tight connections. This device is intended to feed the oil automatically with the air compression piston in motion and when the air compression piston ceases motion in the cylinder the vacuum is released in the feed 70 pipe and thus the oil ceases to flow. The air valve A which allows the air compression cylinder to become filled with air is sufficiently large to allow an unrestricted flow of air into the air compression cylinder 75 so that the maximum efficiency of the air compression cylinder is maintained, the air valve spring being so tensioned that it will not hinder the compression volume of the air compression cylinder, yet holds the valve 80 in closed position when the air cylinder is not being charged. The vacuum valve B in the oil feed pipe is held to its seat with the coil spring and this valve and its coil spring 85 are so arranged that said valve will operate 90 with a slightly less pull from the air compression cylinder than the air inlet valve that charges the cylinder with air. The oil is placed in the reservoir or lubricator and passes into the tube 6 reaching almost to 95 the bottom of the oil reservoir, thence up the tube to the regulating valve, then into the sight feed and through the oil feed pipe 11 into the air cylinder.

It is thought that the construction, operation, and advantages of this invention will now be quite apparent to those skilled in the art without a more detailed description thereof. The present embodiment of the invention has been disclosed in detail merely 100 by way of example since in actual practice it attains the features of advantage enumerated as desirable in the statement of the invention and the above description. It will be apparent that changes in the details of construction, and in the combination and arrangement of parts may be resorted to 105 110

without departing from the spirit and scope of the invention as hereinafter claimed or sacrificing any of its advantages.

Having thus described the invention, what I claim as new is:—

A device for automatically controlling the feeding of oil to an air compressing cylinder comprising in combination a valve casing formed with a valve seat therein and having means to engage the casing in communication with the cylinder, an air inlet, a check valve in the casing closable against the seat away from the cylinder, spring means urging the valve against the seat, a

second valve casing tapped into the first mentioned valve casing to extend laterally therefrom, a valve seat in said second mentioned casing, an oil check valve in the second mentioned casing closable against the seat therein away from the first mentioned casing, spring means urging the second mentioned check valve closed against the second mentioned seat, and means for connecting the end of the second mentioned casing remote from the first mentioned casing with a source of oil.

In testimony, whereof I affix my signature.

GEORGE F. TURNER.
